THREADING TOOL

Willard E. Parish, Syracuse, N. Y.

Application January 4, 1939, Serial No. 249,271

8 Claims. (Cl. 10—103)

This invention relates to threading tools and more particularly to threading tools of the chaser type by which the thread is completely cut by one pass of the tool.

5 Considerable difficulty is experienced in cutting a smooth and uniform thread in metals due to the fact that the thread is in the nature of a groove, the bottom of which, in the case of the V threads and Acme threads, is comparatively narrow, and the sides of the thread extend in angular relationship, whereby the cutting tool is of 10 more or less pointed formation and cuts the thread on both sides of the groove. There is accordingly no opportunity to provide side rake 15 extending from both sides or cutting edges of the pointed tool. This results in the chips coming off from each side or edge of the tool, meeting over the top of the tool and immediately becoming bound and wedged together with the result 20 that the tool tears the work making the thread rough and uneven.

This situation is particularly true in connection with the softer metals, such as aluminum, copper etc., due to the characteristics of these 25 metals to rag and tear during the cutting operation unless the tool is ground with top or side rake extending at a very appreciable angle. For example, I have found that cutting tools ground with a rake of forty-five degrees produces a 30 much smoother cut in metals such as aluminum and its alloys, than do tools ground with a conventional angle of rake used in iron, steel and like metals.

Accordingly, the problem of cutting a thread 35 in or on metals such as aluminum and copper presents even greater difficulties than the threading of iron, steel, and the harder metals. At the present time, it is attempted to overcome this situation by taking very fine cuts and passing 40 the tool a number of times over the work. This not only consumes a considerable amount of time, but the thread, regardless of how many times the tool is passed over the work, is never smooth and uniform because there is no satisfactory disposal of the chips during the cutting 45 operation.

This invention has as an object a threading tool so formed and arranged as to produce a smooth, uniform and even thread comparable to a milled 50 thread by only one pass of the tool.

The invention further includes a tool of the type referred to which may be conveniently and quickly adjusted after grinding operations.

55 The invention consists in the novel features

and in the combinations and constructions hereinafter set forth and claimed.

In describing this invention, reference is made to the accompanying drawing in which like characters designate corresponding parts in all the 5 views.

Figure 1 is a sectional view of a threading tool and holder therefor involving my invention.

Figure 2 is an end elevational view of the threading tool and contiguous portion of the 10 holder looking to the right Figure 1.

Figure 3 is an enlarged fragmentary view of the cutting portion of the cutters shown in Figure 2.

Figure 4 is an enlarged fragmentary detail 15 view taken on line 4—4, Figure 2.

Figure 5 is an enlarged diagrammatic view showing the relative formation of the cutters arranged in superimposed position.

The cutters here shown are of disk formation 20 secured together as a unit and carried by a suitable holder. The cutters consist of disks 10, 11, 12, 13 and 14. The cutters 10, 11 and 12 are in the nature of roughing cutters, and the cutters 13 and 14 are finishing cutters. It will be apparent as the description proceeds that the cutters may be of any general formation. I prefer the disk formation inasmuch as it is more economical than others. It will also be apparent that the roughing cutters 10, 11 and 12 may be 30 formed of one integral piece and likewise the finishing cutters 13 and 14.

The disks 10 to 14 are turned to the proper size and the periphery turned to the proper formation as in the case of conventional circular form cutters. The disks are subsequently machined or ground off as at 15 to form a cutting portion. Thereafter, it is only necessary to grind the top surface of the cutting portion until the entire periphery of the disk is used up.

40 It will also be understood that in the event separate disks are used to form the roughing cutter, and separate disks are used to form the finishing cutter, the thickness of the disk will be determined by the pitch of the thread to be cut. 45 For example, if an eight pitch thread is to be cut, the individual disk will be $\frac{1}{8}$ of an inch in thickness. The disks 10, 11 and 12, constituting the roughing cutters, are arranged to progressively cut the thread to full depth, as indicated in 50 Figure 1, and more clearly in Figure 4. The included angle of the cutting edges 16 is slightly less than the included angle of the thread to be cut. In other words, the grooves of the thread cut by the roughing cutters 10, 11 and 12 is of 55

less width than the groove of the finished thread. That is, the roughing cutters are so formed as to leave some material to be removed by the finishing cutters. The roughing cutters are formed with top rake 17, see Figures 2 and 3, the angle shown being substantially forty-five degrees, which has been found most suitable for certain aluminum alloys. The base of the cutting portion of the disks 10, 11 and 12 is ground circular as at 18, and after the cutters are assembled this surface is ground on an angle of approximately fifteen degrees extending in direction opposite from the finishing cutters 13, 14, as more clearly shown by the surfaces 19, 20 and 21, Figure 3. This surface aids in disposing of the chips formed by the cutting surfaces of the disks 10, 11 and 12. However, the actual cutting surfaces of the roughing cutters are not provided with side rake and accordingly, the thread produced by these cutters is rough and uneven as is the case with conventional threading tools as previously referred to.

The finishing cutters 13, 14 are so formed and arranged that each cuts one side only of the thread. 22 designates the cutting edge of the cutter 13, and 23 the cutting edge of the cutter 14. These edges 22, 23 extend radially from the work and the included angle between the edges 22, 23 is complementary to the included angle of the finished thread being cut. The cutters 13, 14 further distinguish from the roughing cutters in that they are provided with side rake extending from each of the cutting edges 22, 23 transversely across the cutters and preferably this rake is ground to extend at right angles to the cutting edges. That is, the surfaces 24, 25 of the cutters 13 and 14 extend downwardly from the edges 22, 23, the lines 26, 27 indicating the inner wall extending upwardly from these surfaces and also indicating that the surfaces are ground perpendicular to the edges 22, 23. Also, I prefer that the cutters 13, 14 do not extend entirely to the bottom of the groove cut by the roughing cutter 12.

45 The relative form of the cutters is illustrated in the diagram Figure 5, the cutter 10 ending at 28, the cutter 11 ending at 29, and the cutter 12 at 30. The sides of these cutters 10, 11 and 12 are indicated by the dotted lines at 16. The 50 finishing cutters 13, 14 terminate at 31.

The arrangement shown is for cutting external right hand threads and the tool is accordingly moved to the left during the cutting operation. The cutters 10, 11 and 12 successively engage the work and groove the same to the full depth. Subsequently, the cutter 13 engages the work. However, only the edge 22 thereof engages the left hand side of the rib of the thread and subsequently the edge 23 of cutter 14 engages the opposite side of the thread. Due to the fact that the cutters 13, 14 are formed with an appreciable side rake, the opposite edges 34, 35 extend at a lesser angle than the edges 22, 23 and accordingly, do not engage the thread. The result is 65 that the chip removed by the edges 22 and 23 is neatly sheared from the work and is permitted to pass down the surfaces 24, 25 without any interference. Accordingly, one pass of the tool will produce a smooth, even and uniform thread 70 which excels the more costly milled thread in that there are no waves or cutter marks on the surface of the thread.

In high pressure oil and gasoline lines, where it is necessary to have an absolutely perfect 75 thread in order to effect a liquid tight joint, the

milled thread is not satisfactory due to the waves or cutter marks produced by the milling cutter.

The cutters 10, 11, 12, 13 and 14, in combination with the holder shown in Figures 1 and 2, form a particularly efficient threading tool and one which may be quickly and conveniently adjusted after grinding operations. This holder consists of a shank member 40 provided with a transversely extending internally threaded bore to receive a sleeve 41 which is also threaded internally to receive a stem on which the disks or cutters are mounted. One end of the stem is provided with a shoulder 42, and the contiguous portion 43 is of such diameter as to slidably receive the disks which are secured thereto against rotary motion by a key 44. The opposite end of the stem is formed with surfaces 45 to receive a wrench, or other instrumentality, for threading the stem into the sleeve 41.

The pitch of the threads in the shank 40 and the external threads on the sleeve 41 are of different pitch than the internal threads of the sleeve and those on the stem, and the pitch of both sets of threads extends in a direction such that the cutting pressure on the cutting disk 10 will thread the stem into the sleeve 41 and the sleeve into the shank 40 to clamp the disks between the head 42 of the stem and the side of the shank. For example, in Figure 1 both sets of threads are left hand in direction, whereby the downward pressure on the cutting surfaces of the disks 10 to 14 tends to rotate the disks and the stem in a counter-clockwise direction Figure 2. Accordingly, the threads on the stem being left hand, this movement causes the stem to thread into the sleeve 41, and by the same token because the sleeve 41 is threaded into the shank from the opposite side, it tends to move the sleeve 41 to the right Figure 1. Due to the fact that the sets of threads are of different pitch, the stem is locked rigidly to the shank 40.

This construction permits the cutters to be quickly and conveniently adjusted after a grinding operation. It will be understood that the cutting surfaces of the disks 10 to 14 are ground slightly below the center of the disks and thereafter the threading tool is adjusted so that the points of the cutting surfaces are on the center of the work. This effects front clearance for the tool. This method of obtaining front clearance on a circular tool is conventional practise.

With the structure herein described, the disks 10 to 14 may be removed from the stem and ground separately on a suitable grinding arbor or fixture, the setting for the grinding operation, of course, being relatively positioned on all cutters by the keyway to receive the key 44. After the cutters are ground and again assembled on the stem, the stem may be rotated until the newly ground cutting surfaces are properly positioned and are then locked in this position by threading the sleeve 41 outwardly, or to the right Figure 1. This adjustment may be minute, due to the fact that there are no fixed surfaces or serrations between the stem and the shank of the tool.

What I claim is:

1. A threading tool having a portion arranged to rough cut the thread and a portion to finish the thread to proper form, said latter portion having a pair of cutting edges, one of said edges being arranged to cut one side only of the thread, and the other edge being arranged to cut the opposite side only of the thread, said finishing portion being ground with side rake extending trans-

versely from one cutting edge and extending transversely in opposite direction from the other cutting edge.

2. A threading tool having a portion arranged to rough cut the thread and a portion to finish the thread to proper form, said latter portion having a pair of cutting edges, one of said edges being arranged to cut one side only of the thread, and the other edge being arranged to cut the 10 opposite side only of the thread, said finishing portion being ground with side rake extending transversely from each cutting edge and at right angles thereto.

3. A threading tool comprising a roughing cutter and a pair of finishing cutters, said roughing cutter being arranged to cut the thread to substantially full depth, one of said finishing cutters being arranged to cut one side only of the thread, and the other finishing cutter being arranged to cut the opposite side only of the thread, each of said finishing cutters being formed with a side rake extending transversely from the cutting edge of the cutter and at right angles thereto.

25 4. A threading tool comprising a plurality of cutters secured together as a unit, said cutters being of general disk formation, a plurality of said cutters being formed and arranged to progressively cut the thread to full depth, and a pair of said cutters being arranged to subsequently finish the thread to size, each of said last mentioned cutters cutting on one side of the thread only, and each being formed with side rake extending transversely from the cutting edge of each cutter and at right angles thereto.

5. A cutting tool comprising a stem formed with a shoulder, a circular cutter mounted on said stem and being secured against rotation relatively thereto, a holder formed with an internally threaded aperture, a sleeve threaded in said aperture, said stem being threaded into said sleeve, the threads on said stem and the internal threads of said sleeve being of different pitch than the threads on the exterior of the sleeve and in said holder, said stem being operable when threaded into said sleeve to clamp the cutter between the holder and the shoulder on said stem,

and the pitch of all of said threads extending in a direction to thread the stem in the sleeve.

6. A threading tool having a portion to rough cut the thread with an included angle less than the included angle of the finished thread and a portion to finish the thread to proper form, said latter portion having a pair of cutting edges extending complementary to the included angle of the finished thread, one of said cutting edges being arranged to cut one side only of the rough 10 cut thread, and the other edge being arranged to cut the opposite side only of the rough cut thread, said finishing portion being ground with side rake extending transversely in opposite directions from each cutting edge.

7. A threading tool comprising a plurality of cutters, a group of said cutters acting to rough cut the thread, and a pair of said cutters acting to finish the thread to proper form, said group of roughing cutters being formed to rough cut the 20 thread with an included angle less than the included angle of the finished thread, said pair of finishing cutters being formed with cutting edges arranged in angular relationship, the included angle between said cutting edges corresponding to the included angle of the finished thread, one of said edges being arranged to cut one side only of the thread, and the other edge being arranged to cut the opposite side only of the thread, and each of said finishing cutters being ground with side rake extending transversely in opposite direction from each cutting edge.

8. A threading tool comprising a plurality of cutters arranged in a common plane extending parallel with the axis of the work, a group of 35 said cutters acting to progressively roughcut the thread and an adjacent pair of said cutters acting to finish the thread to proper form, said finishing cutters being formed with confronting cutting edges, one of said finishing cutters being formed with a side rake extending transversely from the cutting edge of said cutter, and the other finishing cutter being formed with a side rake extending transversely from the cutting edge of the second cutter in opposite direction to the rake of the first finishing cutter.

WILLARD E. PARISH.
